UNITED STATES PATENT OFFICE.

JAMES P. T. DONAHUE, OF CHICAGO, ILLINOIS.

ATTACHMENT PLUG.

Application filed April 15, 1922. Serial No. 552,973.

To all whom it may concern:

Be it known that I, JAMES P. T. DONAHUE, a citizen of the United States of America, and a resident of Chicago, county of Cook, and State of Illinois, have invented a new and useful Improvement in Attachment Plugs, of which the following is a specification.

This invention relates to electrical attachment plugs.

The main objects of this invention are to provide an improved form of electrical attachment plug of simple construction, having its parts so arranged that one section of the plug is free to swivel on the other without injury to the parts or danger of short circuiting any of the connections; and to provide an improved form and arrangement of the separable parts to permit of their connection by a straight line movement of one part toward the other.

An illustrative embodiment of this invention is shown in the accompanying drawings, wherein—

25 Figure 1 is a vertical section of the plug showing the parts assembled.

Fig. 2 is a side elevation of the terminal part of the plug.

Fig. 3 is a central vertical section of the 30 socket member.

Fig. 4 is a vertical section of the socket member with the metallic ferrule removed, the view being taken at right angles to the view shown in Fig. 3.

Fig. 5 is a perspective view of the socket member shown in Fig. 4.

Attachment plugs which are now in general use consist of two separable parts, the terminal member of which carries a pair of contact prongs attached to the flexible conductor, and which are adapted to fit into small sockets formed in the base member of the plug for closing the circuit. This form of plug has the disadvantage that in the 40 dark or in a place where the base member of the plug is out of normal view, as, for instance, underneath a table, it is difficult to insert the two prongs into the sockets of the base member without first feeling for the connection.

50 The present invention overcomes this ob-

jectionable feature by having the terminal part of the plug formed with one centering contact stem which is adapted to enter a single flaring socket in the base member for making the connection. This form of connection also permits a swivel movement between the connected parts, so that the plug may be screwed into the lamp socket without twisting the flexible conductor.

In the form shown, the improved attachment plug comprises a socket part or body member 1, adapted to be screwed into a lamp socket, and a detachable terminal part 2, carried by a flexible conductor 3.

The body member 1 is formed of suitable insulating material, and has secured to its periphery the usual metallic ferrule 4. Extending inwardly from one end of the body member, is an axially arranged socket 5, which is adapted to receive a corresponding member on the terminal part. The socket 5 is bell-mouthed as shown at 6, to facilitate the reception of the terminal part so as to permit the terminal part to be readily guided into engagement with the contact elements in the socket member. Extending radially through the body member 1, and intersecting the socket 5, is a rectangular slot 7, arranged to permit the insertion into 70 the socket 5 of a U-shaped spring contact clip 8. The clip 8 is secured to the body member by having its base part connected to an axially disposed contact pin 9, which protrudes beyond the body to form one of 75 the contact elements. The walls of the slot 7 coat with the clip 8 to secure the clip against turning in the socket 5.

Extending through the side wall of the body member 1, at substantially right 80 angles to the clip 8, is a radially disposed slot or opening 10, through which extends a resilient tongue 11, which is arranged to form one of the contact elements. The inner end of the tongue 11 extends into the 85 socket 5, and is normally inclined toward the mouth of the socket, as shown in Figure 3. The outer end of the tongue 11 is secured by a screw 12 to a rigid L-shaped conductor member 13, seated in a peripheral depression 14. The member 13 protrudes 100 beyond the body member into contact with

the ferrule 4, which is depressed on opposite sides of the conductor to form a pair of shoulders 15, which coact with the conductor member for locking the ferrule to the 5 socket member. If desired, the ferrule may be soldered to the member 13 to secure the ferrule 4 and socket member 1 against relative movement.

The terminal part 2 is also formed of insulating material, and in the form shown, 10 comprises a base 16, and an axially arranged stem 17. Mounted on the base 16, is a pair of terminals in the form of binding posts 18 and 19, which are enclosed by a threaded 15 dome-shaped cap 20, centrally apertured to receive the flexible conductor 3, which is connected to the binding posts 18 and 19. Extending axially through the stem 17 is a contact pin 21, arranged for contact with 20 the resilient tongue 11 of the socket member.

The second contact element of the terminal part consists of an annular block 22, which is seated in a recess 23, formed on the 25 stem 17. Interposed between the block 22 and the contact head of the pin 21, is an insulator 24, which is centrally apertured to receive the pin, and which is also recessed to receive the reduced end of the stem 17. 30 The block 22 is arranged to coact with the spring clip 8, when the terminal part is inserted into the socket member. Formed in the terminal part, is a longitudinally extending hole, through which extends a rigid 35 L-shaped conductor 25, which bears at its inner end against the block 22, and at its outer end is connected to the binding post 19.

When it is desired to close the circuit, the 40 stem 17 of the terminal part is inserted into the socket 5, so as to bring the contacts 21 and 22 into engagement with the tongue 11 and clip 8 respectively. The coaction of the block 22 and clip 8 detachably secures 45 the two separable parts of the plug in their assembled relation. The swivel connection between the separable parts of the plug permits the body member to be unscrewed from the lamp socket without turning the terminal part or twisting the conductor 3.

Although but one specific embodiment of this invention has been herein shown and described, it will be understood that numerous details of the construction shown may 55 be altered or omitted without departing from the spirit of this invention as defined by the following claims.

I claim:

1. An attachment plug including a body 60 member having an axially arranged socket extending inwardly from one end thereof and having a radially disposed intersecting slot extending inwardly from one side thereof, said slot being arranged to permit the 65 insertion of a clip into said socket, a con-

tact point mounted on the other end of said member, a spring clip seated in said socket and connected to said contact point to form one of the contact elements, and a radially disposed yielding tongue extending into said slot and intersecting the axis of said socket to form the other contact element. 70

2. An attachment plug including a body member having an axially arranged socket extending inwardly from one end thereof and having a radially disposed intersecting slot extending inwardly from one side thereof, said slot being arranged to permit the insertion of a clip into said socket, a contact point mounted on the other end of said member, a U-shaped spring clip seated in said socket and connected to said contact point to form one of the contact elements, said clip and the walls of said slot coacting to secure said clip against turning, and a radially disposed yielding tongue extending into said slot and intersecting the axis of said socket to form the other contact element. 80

3. An attachment plug including a body member having an axially arranged socket extending inwardly from one end thereof and having a radially disposed intersecting slot extending through said member so as to form a pair of diametrically opposed openings in the periphery of said member to permit the insertion of a clip into said socket through either of said openings, a contact point mounted on the other end of said member, a spring clip seated in said socket and connected to said contact point to form one of the contact elements, and a resilient tongue extending transversely into said slot to form the other contact element. 90

4. An attachment plug including a body member having an axially arranged socket extending inwardly from one end thereof and having a radially disposed intersecting slot extending through said member so as to form a pair of diametrically opposed openings in the periphery of said member, a contact point mounted on the other end of said member, a U-shaped spring clip seated in said socket and connected to said contact point to form one of the contact elements, said clip and the walls of said slot coacting to secure said clip against turning, each of said diametrically opposed openings being of sufficient size to permit the insertion of said clip into said socket during the assembly of said body member and clip, and a radially disposed resilient tongue extending transversely into said slot and intersecting the axis of said socket to form the other contact element. 100

5. An attachment plug including a body member having an axially arranged socket extending inwardly from one end thereof, a contact point mounted on the other end of said member, a spring clip seated in said 110

120

125

130

socket and connected to said contact point to form one of the contact elements, a metallic ferrule mounted on the periphery of said member, said body member having a radially disposed opening extending through the side wall thereof and having a peripheral recess formed adjacent the outer end of said opening, a resilient tongue extending through said opening to form the other contact element, the inner end of said tongue being located in said socket and the outer end being seated in said recess, and a rigid conductor seated in said recess and secured to said tongue, said conductor having a part protruding beyond said body member into contact with said ferrule.

Signed at Chicago this 13 day of April, 1922.

JAMES P. T. DONAHUE.
